BOILER

Carl Z. Alexander, Hopatcong, N. J.

Application January 23, 1947, Serial No. 723,694

2 Claims. (Cl. 122—37)

1

This invention relates to improvements in boilers, and more particularly pertains to a boiler of novel construction adapted to operate at a high degree of efficiency.

The invention is more particularly described hereinafter and illustrated in the accompanying drawings, wherein.

Fig. 1 is a perspective view of a boiler embodying my invention.

Fig. 2 is a fragmentary and elevational view thereof, taken on line 2—2 of Fig. 1.

Fig. 3 is a vertical, longitudinal, sectional, elevational view thereof, taken on line 3—3 of Fig. 4.

Fig. 4 is a vertical, transverse, sectional view thereof, taken on line 4—4 of Fig. 3.

Fig. 5 is a horizontal, sectional view thereof, taken on line 5—5 of Fig. 4, and

Fig. 6 is a fragmentary, vertical, elevational view, taken on line 6—6 of Fig. 3.

As shown in the drawings, the boiler embodying my invention comprises a casing of generally inverted U-shaped cross-section having a top portion 11 (preferably arcuate) and parallel spaced side plates 12 and 13 and end plates 14, 15 integral therewith or secured thereto, defining a generally rectangular, closed casing (see horizontal cross-sectional view, Fig. 5). A plurality of hollow tubes 16, 17 and 18 are fixed to the end plates 14 and 15, said closed tubes defining thermal generator heads. Baffle plates 19 and 20 are fixed to the side plates 12 and 13 and are provided with medially, angularly directed portions, as at 19a, 20a directed toward the respective opposite side plates. Said medially directed portions 19a, 20a are aligned intermediate adjacent tubes 16, 17 and 18, and are of V-shaped horizontal cross-section, to direct the products of combustion in their upward passage uniformly around the tubes 16, 17 and 18, for more uniform bathing of the tubes in said gases and heating of the tubes throughout their length than would occur if the gases flowed freely upwardly to the flue. The baffle plates are medially of V-shaped cross-section (see Fig. 5) to direct the gases more closely to the longitudinal centers of said tubes 16, 17, 18 externally. Without this construction, the gases passing from combustion chamber 21 to flue pipe 23 would probably tend to pass upwardly close to the side plates 14, 15, concentrating their heating action along the ends only of said tubes. The baffles 19, 20 shown and described herein are designed to deflect the gases sinuously so as to assure more uniform heating of the tubes 16, 17, 18 throughout their

2

length to attain higher efficiency in operation. Thus, the tubes are externally heated, in a novel and effective manner. The lower end of the casing defines a hollow combustion chamber 21 below the tubes 16, 17, 18 to which an energy source 22 is connected. Such energy source may be, for example, an oil burner unit, as shown in the drawings, or may be any other source of energy suitable for the purpose.

The casing is provided with a flue pipe 23 at the upper end thereof to carry off the products of combustion after the same have passed upwardly within the casing and around the tubes 16, 17 and 18, said tubes being medially disposed in said casing in vertically aligned relation intermediate and spaced from the side plates 12 and 13, which, with the baffle plates 19, 20 define a sinuous passageway 10 around said tubes 16, 17, 18 for the products of combustion, which are thus obliged to completely bathe the tubes 16, 17 and 18 before passing through the flue 23.

A cold water feed pipe 24 connection is attached to one of the tubes 16, 17 or 18. The uppermost tube has connected thereto a steam outlet pipe 25 which may be connected in the conventional manner with the work to utilize the steam generated by the boiler when the boiler is used for steam generation purposes (or the hot water developed therein, when it is used for hot water heating systems). Feed back nipples 27 and 26 pass through registering apertures in adjacent portions of tubes 16, 17 and 18 and connect such adjacent tubes. Geyser pipes 28 and 29 pass through said nipples, the free ends 28a, 29a of said geyser pipes projecting into the tubes 17 and 18 and being preferably curved or angularly directed to terminate at the circumferences of the nipples. The lower ends of said geyser pipes are connected to apertured cup bases 30 and 31 through which water may pass from the tubes 16 and 17, to carry the same upwardly into the next adjacent tube. The geyser pipes are provided with guide rings 32 and 33 which are disposed in the nipples 27 and 26. The base or cup end 30 of the geyser pipe 28 rests in a water chamber 34 dependent from the lowermost tube 16 and opening thereinto.

In operation, the source of energy 22 heats the tubes 16, 17 and 18, the hot water from each of the two lower tubes 16 and 17 being carried to the tubes thereabove through the geyser pipes 28 and 29. It will be noted that the chamber 34 provides the lower tube 16 with a very high column of water, which is desirable to obtain a maximum geyser action through the geyser pipe

28 positioned in the lowermost tube 16, which has the highest column of water. The cup base 31 of geyser pipe 29, as shown in Fig. 6, is preferably of generally arcuate cross-section, of a reverse outline to that of the arc of the tube 17 on which said base 31 is positioned, the ends of said cup 31 being partly closed as at 45 to define openings 46 through which water passes from said tube 17 upwardly through the geyser pipe 29 and into the uppermost tube 18. The cup 31 may be tack welded as at 47 along its lower edges to the bottom of tube 17. The construction of the geyser pipe base 31 as shown in Fig. 6 provides for the continuous flow of water under steam temperature for the use of the boiler as a steam boiler. If the water in the tubes 17 and 18 rises above the water lines 17a, 18a defined by the upper ends of the nipples 27 and 26, such surplus water will feed back to the next lowermost tube through said nipples.

The boiler may be provided with such standard accessories as a safety valve and pressure gauge (35 and 38 respectively) preferably connected to the uppermost tube 18, water gauge and low water cut-off valve (36 and 37) preferably connected to the lowermost tube 16, and with a flue pipe control unit or switch 39 which is connected to the flue pipe 23 and to the oil burner unit 22 and is electrically operated in the conventional manner, when an oil burner is the source of energy.

A hot water coil 42 may be positioned within one of the tubes 16. A blow-down valve 40 is connected as at 41 to the lower end of the tube 18 to facilitate cleaning the same.

The end plate 15 is provided with an aperture 43 in registry with the lowermost tube 16, said aperture being normally closed by the head plate 44 bolted to said end plate 15 as at 44a. By this arrangement, it is possible to readily clean the lowermost tube 16 from time to time, if desired. The boiler casing may be provided with external insulation 48 which may be of spun glass or other insulating medium.

Fig. 3 shows the use of the boiler as a steam generating boiler, in which case the tubes 16, 17 and 18 are only partly filled with water. The invention is adapted for use in hot water systems, in which case the entire boiler would be filled with water; the arrangement of the geyser pipes 28 and 29 and other parts would be the same as that shown in Fig. 3. The geyser pipes would then serve to produce rapid internal circulation and increase the efficiency of the boiler.

It will be noted that each of the thermal generator heads (16, 17 and 18) is a separate generator and maintains its own water line. The arrangement of the baffle plates 19, 20 in addition to providing for uniform distribution of the heat in its passage from the combustion chamber 21 to the flue 23, serves to keep the boiler casing clean, preventing the accumulation and deposit of soot.

I have found that a steam boiler having three tubes 16, 17 and 18, as shown and described herein, is highly efficient and will develop steam pressure in a very short time interval, but the number of tubes may be increased or decreased without departing from the spirit and scope of the invention. The term "plurality" as used herein shall accordingly be deemed to mean two or more. While the tubes 16, 17 and 18 have been shown as of circular cross-section they may be made of a non-circular, cross-section, if so desired.

While I have shown in the drawings and described in the above specification, a convenient form of structure embodying my invention, it will be apparent from such disclosure that the invention is capable of many modifications without departing from the spirit and scope thereof, as set forth in the appended claims.

Having thus described my invention, what I claim as new and desire to secure by Letters Patent is:

1. A boiler comprising a casing, the casing comprising spaced parallel end and side plates, means securing said plates along corresponding edges, a top portion disposed over the corresponding top edges of said plates, a hollow combustion chamber in the base of the housing, a heat source for the combustion chamber; the boiler further comprising at least three hollow tubes disposed in the end plates above the combustion chamber in spaced vertically aligned relation and intermediate the side plates, the bottom and intermediate tubes being provided with registering apertures at one end and the intermediate and upper tubes being provided with registering apertures at the opposite end, a nipple disposed through the apertures and extending upwardly in each of the higher tubes, the bottom tube being further provided with a water chamber of substantial depth and arcuate base aligned with the registering apertures, a geyser tube disposed in the water chamber in the bottom tube and extending upwardly through the nipple to the top edge thereof in the intermediate tube, the base of the geyser tube being arcuate in the opposite direction to the arcuate base of the water chamber, a second geyser tube disposed in the intermediate tube below the registering apertures in the intermediate and upper tubes and extending upwardly through the nipple to the top edge thereof in the upper tube, means introducing water into said tubes and means removing steam therefrom; the boiler further comprising baffle plates of V-shaped horizontal cross section, means attaching the base of the plates to the spaced parallel side plates intermediate the adjacent hollow tubes with the ridge of the baffle plates directed toward the respective opposite side plates and adapted to direct the products of combustion in their upward passage uniformly around the hollow tubes, and means removing the products of combustion.

2. A boiler comprising a casing, the casing comprising spaced parallel end and side plates, means securing said plates along corresponding edges, a top portion disposed over the corresponding top edges of said plates, a hollow combustion chamber in the base of the housing, a heat source for the combustion chamber; the boiler further comprising a plurality of hollow tubes disposed in the end plates above the combustion chamber in spaced vertically aligned relation and intermediate the side plates, adjacent tubes being provided with registering apertures at alternate ends, a nipple disposed through the apertures, said nipple extending upwardly in each of the higher tubes and adapted to maintain the water level, the lowermost tube being further provided with a water chamber of substantial depth and arcuate base aligned with the registering apertures, a geyser tube disposed in the water chamber in the bottom tube and extending upwardly through the nipple substantially to the top edge thereof in the next higher tube, an apertured cup base for the geyser tube,

the base being arcuate in the opposite direction to the arcuate base of the water chamber, another geyser tube disposed below the registering apertures in adjacent tubes and extending upwardly through the nipple substantially to the top edge thereof in the next higher tube, an apertured cup base for the geyser tube, a blow-down valve for at least one of the hollow tubes and adapted to facilitate cleaning; an aperture in one of the parallel end plates of the casing in registry with one end of the lowermost hollow tube, said tube being open at that end, a head plate for the aperture and open end of the hollow tube and means releasably securing the head plate over the open end of the hollow tube and adapted to close the aperture in the end plate and the open end of the hollow tube; the boiler further comprising a hot water coil disposed in one of the hollow tubes, means circulating water in and out of said coil, means 20

introducing water into the hollow tubes, means removing steam therefrom baffle plates of V-shaped horizontal cross section, means attaching the base of the plates to the spaced parallel side plates intermediate the adjacent hollow tubes with the ridge of the baffle plates directed toward the respective opposite side plates and adapted to provide uniform distribution of the heat about the hollow tubes, and means removing the products of combustion.
